CLAIM

The ornamental design for a buckle for weight belt, as shown and described.

DESCRIPTIONFIG. 1 is a front, top and right side perspective view of a buckle for weight belt showing my new design;
FIG. 2 is a front elevational view thereof;
FIG. 3 is a left side elevational view thereof, the right side being a mirror image thereof;
FIG. 4 is a rear elevational view thereof;
FIG. 5 is a bottom plan view thereof; and,
FIG. 6 is a cross-sectional view taken generally along the line 6—6 of FIG. 5.
